UNITED STATES PATENT OFFICE.

FREDERICK F. VINDEMORE, OF FAIRVIEW, NEW JERSEY.

COMBINED FUSE-PLUG AND CIRCUIT-CLOSER.

No. 908,174.

Specification of Letters Patent.

Patented Dec. 29, 1908.

Application filed March 7, 1908. Serial No. 419,682.

To all whom it may concern:

Be it known that I, FREDERICK F. VINDEMORE, a citizen of the United States, and a resident of Fairview, in the county of Bergen and State of New Jersey, have invented a new and Improved Combined Fuse-Plug and Circuit-Closer, of which the following is a full, clear, and exact description.

This invention relates to certain improvements in means for closing one electric circuit preferably of high potential, by the operation of an electromagnet energized upon the closing of a second circuit preferably of low potential, and more particularly to certain improvements, whereby the circuit closer is combined with the fuse plug and the two supported upon a single base.

In certain constructions it is customary to provide a plug of non-conducting material carrying a fuse wire and so constructed that when the plug is screwed into place, the fuse wire is brought into circuit. Should the fuse wire burn out, the entire plug may be removed, the electromagnet secured to a new plug, and the latter replaced in position.

In my improved construction I provide an electromagnet adjacent the plug and adapted to be operated by the closing of a secondary circuit. The operation of the electromagnet serves to close the circuit adjacent the plug and permit the passage of the current through said plug and its fuse.

Reference is to be had to the accompanying drawings, forming a part of this specification, in which similar characters of reference indicate corresponding parts in all the figures, and in which—

Figure 1 is a central longitudinal section through a device constructed in accordance with my invention, and showing diagrammatically an arrangement of the primary and secondary circuits; Fig. 2 is a section on the line 2—2 of Fig. 1; Fig. 3 is a view of the inner end of the socket for receiving the plug, together with the mechanism for holding the same in place; and Fig. 4 is a plan view of one form of connecting member between the plug and one of the main conductors.

In the specific form of my device illustrated in the accompanying drawings, I employ a base 10 of insulating material and adapted to be secured in any suitable manner to the wall or ceiling. The base is provided with two transverse grooves for receiving and supporting the two main insulating conductors 11 and 12, and is also pro-

vided with a flange or wall 13 for separating the socket which receives the fuse plug from said conductors, so as to prevent any possibility of short-circuiting the device. At the opposite side of the curved wall 13 from said conductors, there is secured in place a socket 14, preferably formed of sheet metal and threaded to receive the plug 15. The socket is rigidly held in place, preferably by the mechanism illustrated in detail in Fig. 3. The inner end of the socket is provided with inwardly-directed flanges 15*, and extending laterally into the opening in the side of the socket and engaging with the inner surfaces of the two flanges, is a clamping plate 16. The plate is provided with a central aperture 17 and two smaller threaded apertures 18 in the portions overlapping the flanges 15*. Two screws 19 extend outwardly from the inner surface of the base through a portion thereof and through the flanges 15* into the threaded apertures 18 of the said clamping plate. The lower end 20 of the clamping plate is provided with an aperture through which extends a combined clamping screw and binding post 21, which serves for holding the clamping plate to the base and also permits of the attachment of a wire 22 to said clamping plate. The socket 14 is thus rigidly held in place and electrically connected to the binding post 21 and wire 22.

Screw-threaded into the socket 14 is the plug 15 previously referred to. The body 23 of said plug is preferably formed of insulating material, and encircling the lower portion thereof, which screws into the socket, is a shell or covering 24 of sheet metal. Extending outwardly through the center of the plug is a tube of insulating material 25, which is spaced from the outer wall to leave an annular chamber, within which is disposed the fuse 26. The fuse at one end is connected through an aperture in the side wall to the outer metal casing 24, and connected at the other end with a collar 27 at the inner exposed end of the plug. Extending through the tube 25 is a rod 28, having a collar 29 carried thereby adjacent the collar 27 of the plug, and the inner end of the rod extends beyond the collar through the aperture 17 of the clamping plate 16 and through an aperture in the base to the inner side thereof. Contact between the collar 29 or the rod 28 with the clamping plate, is prevented by means of a disk 30 of insulating material within the socket and between the collar 29 and the plate 16. The

rod 28 is longitudinally movable to bring the collar 29 into engagement with the collar 27, but the two are normally held out of engagement with each other by the action of a coil 5 spring 32 encircling the inner end of the rod. Said rod is electrically connected to the conductor 11 by a connecting strip 33, against one end of which the spring 32 engages. The strip extends through an aperture in the base 10 to the outer surface thereof, and is there provided with a separate clamping plate 34, adapted to hold the conductor 11 to the strip upon the tightening of a suitable screw 35.

Encircling the outer end of the plug 15, 15 and preferably threaded to the body thereof, there is provided a sheet metal casing 36, serving to support the coils 37 of an electromagnet. The casing 36 preferably carries two arms 38, connected at their outer ends 20 by a cross bar 39, which latter supports the magnets in the proper position. By adjusting the bar 39 longitudinally of the arms, the position of the magnets in respect to the plug may be adjusted. At the outer end of the 25 rod 28, there is provided an armature 40, disposed adjacent the ends of the cores of the electromagnets. The armature is movable to and from the magnets, the movement in one direction being against the 30 action of the spring 32 and serving to bring the collars 27 and 29 into engagement with each other and to close the circuit, while the movement in the opposite direction is caused by the deenergizing of the magnet and tension of the spring 32.

The current delivered through the conductors 11 and 12 may be used for operating any suitable device desired, as, for instance, the electric arc lights 41. The wire 22 from 40 the binding post 21 leads to one of the arc lights, and the other is connected in any suitable manner to the conductor 12, as, for instance, through a wire 42, shown in dotted lines. The electromagnets 37 are energized 45 in any suitable manner, but preferably from a circuit of low potential, including a battery 43, wires 44 and 45, and a switch 46.

My mechanism is especially designed for use in places where the presence of the high 50 potential current is objectionable, but where it is desired to frequently turn on and off the light, as, for instance, automatically by the operating of certain machinery or mechanism. To mount a switch of the electric 55 lighting or electric power circuit directly on the machine might result in accidental injury to the operator or injuriously affect the work operated upon, but by closing the circuit through an electromagnet and operating 60 the latter by a current of low potential, the wires and switch of the latter current may be disposed at any point desired, without danger. While the switch 46 is closed, the magnets 37 will be energized and the armature 65 drawn into engagement with the cores

thereof. This will permit a passage of the current from the conductor 11 through the strip 33 to the rod 28, collar 29, collar 27, fuse 26, casing 24, socket 14, and clamping plate 16 to the binding post 21. From the 70 binding post, the wire may pass to the lights, machinery, mechanism, or other device to be operated, and thence back to the conductor 12. Should the fuse burn out, the armature may be removed from the rod 28 and 75 the plug screwed out of its socket. A new fuse may be readily inserted and the device returned to its original position.

If it is desired to close the high potential circuit for any suitable length of time and it 80 is not desired to employ the secondary circuit, or in case the secondary circuit is broken or out of order, the plug may be screwed into the socket until the collar 27 firmly engages with the collar 29 and the circuit 85 will be closed independent of the armature 40. The normal distance between the two collars may be controlled at will by varying the distance to which the plug is screwed into its socket. 90

The device may be used in various different positions or with various different mechanisms, but I contemplate particularly using the high potential circuit for lighting purposes in connection with copying or other 95 photographic operations, and mount the switch 46 on the camera or other photographic apparatus, so that when the parts of the latter are in proper position, the lights will be turned on, but as soon as the sensitized plate or ground glass screen is removed 100 from the camera, the secondary circuit will be broken at the switch 46 and the lights will be immediately turned off.

Having thus described my invention, I 105 claim as new and desire to secure by Letters Patent:

1. In combination, a base, a member including a fuse and detachably secured to said base, a circuit-closing member, and an 110 electromagnet carried by said detachable member for operating said circuit-closing member.

2. In combination, a base, a plug detachably secured thereto and including a fuse, an 115 electromagnet carried by said plug, and means whereby the energizing of said electromagnet closes the circuit through said fuse.

3. In combination, a base, a plug screw-threaded thereto and including an annular 120 body and a central tube, a fuse intermediate said body and tube, an electromagnet carried by said plug, a rod extending through said tube, an armature for said magnet and operatively connected to said rod, whereby 125 the energizing of the magnet moves said rod longitudinally, and means carried by said rod for closing a circuit through said fuse upon the energizing of the magnet.

4. In combination, a base, a plug detach- 130

ably secured thereto, a collar carried by said plug adjacent the inner end thereof, a rod extending through said plug and having means adapted to engage with said collar to close an electric circuit, an electromagnet carried by said plug at its outer end, and an armature for said magnet connected to said rod for moving the latter to close the circuit.

5. In combination, a base having a threaded socket, a plug threaded into said socket and including a fuse, a circuit-closing member carried by said plug and within said socket, and an operating rod for said circuit closer and extending through said plug to

15 the outer end thereof.

6. In combination, a base, a member including a fuse and detachably secured to said base, a circuit-closing member within said base and beneath said detachable member, and an operating rod for said circuit closer and extending through said first-mentioned

7. In combination, a base, a plug detachably secured thereto, a circuit closer within said base and beneath said plug, and an electromagnet carried by said plug for operating said circuit closer.

8. In combination, a base, a plug detachably secured thereto, a collar carried by said plug adjacent the inner end and forming a portion of an electric circuit, a collar carried by the plug at the outer end thereof, an electromagnet supported from said last-mentioned collar, and a circuit closer within the base and beneath the plug and adapted to be operated by said electromagnet.

In testimony whereof I have signed my name to this specification in the presence of two subscribing witnesses.

FREDERICK F. VINEDMORE.
